DESIGN FOR A COIN RECEPACLE

Leonard O. D. Harris, Forest City, N. C.

Application February 23, 1940, Serial No. 90,462

Term of patent 7 years

To all whom it may concern:

Be it known that Leonard O. D. Harris, a citizen of the United States of America, residing at Forrest City, in the county of Rutherford and State of North Carolina, has invented a new, original, and ornamental Design for a Coin Receptacle, of which the following is a specification, reference being had to the accompanying drawing, forming a part thereof.

Figure 1 is an isometric view of a coin receptacle, looking at one side thereof; and

Figure 2 is an isometric view looking at the opposite side;

Figure 3 is a vertical sectional view taken along the line 3—3 in Figure 1.

I claim:

The ornamental design for a coin receptacle, as shown.

LEONARD O. D. HARRIS.
